UNITED STATES PATENT OFFICE.

WALTER HOWARD O'BRIEN, OF BRONXVILLE, NEW YORK.

VAULT-LIGHT.

No. 861,883.

Specification of Letters Patent.

Patented July 30, 1907.

Application filed December 6, 1906. Serial No. 346,676.

To all whom it may concern:

Be it known that I, WALTER HOWARD O'BRIEN, a citizen of the United States, residing at Bronxville, in the county of Westchester and State of New York, have invented certain new and useful Improvements in Vault-Lights; and I do hereby declare the following to be a full, clear, and exact description of the invention, such as will enable others skilled in the art to which it appertains to make and use the same.

10 My invention relates to a novel construction in a sidewalk or vault light, the object being to provide a device of this character which is very simple, efficient, cheap and capable of carrying heavy loads without appreciably yielding, and consists in the features of construction and combinations of parts hereinafter fully described and claimed.

In the accompanying drawings illustrating my invention: Figure 1 is a top plan view of a vault light constructed in accordance with my invention. Fig. 2 is 20 a transverse section of the same on the line 2 2 of Fig. 1. Fig. 3 is a longitudinal section of the same on the line 3 3 of Fig. 1. Fig. 4 is a plan view of a modified form of construction of a vault light constructed in accordance with my invention. Fig. 5 is a vertical longitudinal 25 section of the same on the line 5 5 of Fig. 4. Fig. 6 is a detail vertical transverse section on the line 6 6 of Fig. 4. Fig. 7 is a fragmentary detail transverse section of another modified form of construction. Fig. 8 is a fragmentary perspective view illustrating another 30 modification in construction.

In the construction of vault lights it is desirable to incorporate the greatest possible lighting or transparent area compatible with strength and rigidity. It is further desirable that the same be constructed at the least possible expense of labor and material. To these ends 35 my device comprises a base plate 1 of sheet-metal preferably of relatively heavy gage, provided on its edges with up-turned flanges 2.

In the body portion of said plate 1 I provide H-shaped incisions 3 disposed in parallel rows at regular 40 intervals and said rows being regularly spaced. By this means I provide free tongues or flanges 4 which are bent to extend upwardly at right angles to the plane of the body and thus border two opposing edges of each 45 of the rectangular openings 5. All of the said flanges 4 are disposed parallel with each other and extending transversely thereto and abutting against the vertical edges thereof are disposed channel bars 6 having flanges of a depth equal to the depth of said tongues in flanges 50 4 and having the outer faces of their webs resting upon said plate 1, the outer faces of the flanges of said channel bars being disposed in contact with the opposing vertical edges of said tongues or flanges 4 of adjacent rows. The said channel bars 6 are riveted to said plate 55 1 through the webs thereof. Each of said rectangular

openings 5 is thus bordered on all sides by vertical flanges or walls constituting means for supporting the glass prisms 7. Each of the latter consists of a rectangular block of glass having a plane upper face and beveled side edges, and which is provided between its upper and lower faces with a peripheral shoulder 8 adapted to rest upon said supporting means, the lower reduced portion 9 of each prism projecting into the opening or well bordered by said supporting means and serving to maintain said prism centered in the latter. 60 To complete the structure, the recesses between the rows of prisms and surrounding the same, are filled with a suitable cement or concrete 10, which when set will obviously hold said prisms firmly in place and render the structure very inflexible. The structure 70 may be further reinforced by passing rods 11 through the flanges 2 at the ends of the same and which extend parallel with and lie within the channels of said channel bars.

In Figs. 4, 5 and 6, I have illustrated a modified form 75 of construction in which the channel bars 16 are laid so that the outer faces of their webs lie in contact with the vertical edges of the tongues or flanges 4 and are secured in position by means of rivets passing through one of the flanges thereof and through the plate 1. 80 The free ends of the flanges of each two adjacent channel bars 16 are thus opposed and are separated by a space of sufficient width to permit cement or asphalt to be admitted to fill said channel bars and said space and said filling being thus keyed in place. The said filling 85 18 is introduced after the glass prisms 17 are disposed in position over the openings 5 and rest upon the free ends of the tongues or flanges 4 and upon the upper faces of said channel bars 16.

The flanges 2 of the plate 1 are in all instances preferably of such depth that their upper edges flush with the upper faces of the prisms, but such depth is not essential. The construction may be further modified by substituting angle irons 19 for the said channel bars 16 90 as shown in Fig. 7.

In Fig. 8 I have illustrated another modification in construction which consists in employing a corrugated plate 20 and also in employing channel bars 21 having corrugated flanges, said plate being adapted to stiffen the structure and being identical in other features of 100 construction with the plate 1, particular illustration of the openings, etc. being omitted from Fig. 8. The corrugated flanges of the channel bars 21 are adapted to present a larger area for adhesion of the cement filling and are stiffer than plane flanges thus enabling a lighter 105 metal to be employed in their construction.

I claim as my invention:

1. A vault light comprising a plate provided with openings, reinforcing members secured to the said plate and bordering said openings, transparent prisms disposed over 110

- said openings and resting upon the said reinforcing members, and a filling disposed on said plate and embedding said reinforcing members and said prisms, the upper faces of the latter being exposed.
- 5 2. A vault light comprising a plate provided with rectangular openings, flanges bordering each of said openings on two sides thereof, reinforcing members secured to said plate and disposed in contact with the side edges of said flanges, transparent prisms disposed over said openings and resting upon the free ends of said flanges and upon said reinforcing members, and a filling disposed upon said plate and embedding said reinforcing members and said prisms, the upper faces of the latter being exposed.
- 10 3. A vault light comprising a plate provided with openings, parallel reinforcing members secured to the said plate and bordering said openings, transparent prisms disposed over said openings and resting upon the said reinforcing members, and a filling disposed on said plate and embedding said reinforcing members and the upper faces of the latter being exposed.
- 15 4. A vault light comprising a plate provided with rectangular openings, flanges bordering each of said openings on two opposing sides thereof, all of said flanges being parallel with each other, reinforcing members secured to said plate and disposed in contact with the side edges of said flanges, transparent prisms disposed over said openings and resting upon the free ends of said flanges and upon said reinforcing members, and a filling disposed upon said plate and embedding said reinforcing members and said prisms, the upper faces of the latter being exposed.
- 20 5. A vault light comprising a plate provided with a plurality of rows of rectangular openings, reinforcing means secured to the said plate and bordering said openings, transparent prisms disposed over said openings and supported upon said reinforcing means, and a cementitious filling disposed upon said plate and embedding said reinforcing means and said prisms, the upper faces of the latter being exposed.
- 25 6. A vault light comprising a plate provided with openings, reinforcing means secured to the said plate and bordering the said openings, transparent prisms disposed over said openings and supported upon the said reinforcing means, said prisms being of less area on their upper than on their supported faces, and a cementitious filling disposed upon said plate and embedding the said reinforcing means and said prisms, the upper faces of the latter being exposed.
- 30 7. A vault light comprising a plate provided with a plurality of rows of rectangular openings, flanges bordering each of said openings on two opposing sides thereof, reinforcing strips secured to said plate and bordering the remaining sides of said openings, transparent prisms disposed over said openings and supported upon said flanges and said reinforcing strips, said prisms being of greater area on their supported than on their upper faces and a filling disposed upon said plate and embedding said prisms, the upper faces of the latter being exposed.
- 35 8. A vault light comprising a plate provided with a plurality of rows of rectangular openings, flanges integral with said plate bordering each of said openings on two opposing sides thereof, structural iron strips extending over said plate and secured thereto, said strips being disposed to border said openings on the free sides thereof and to abut against the side edges of said flanges, transparent prisms disposed over said openings and supported upon said flanges and said strips, and a filling disposed upon said plate and embedding said strips and said prisms, the upper faces of the latter being exposed.
- 40 9. A vault light comprising a plate provided with a plurality of rows of rectangular openings, flanges integral with said plate bordering each of said openings on two opposing sides thereof, channel bars extending over said plate and resting thereon and secured thereto, said channel bars having the outer faces of their flanges disposed in contact with the side edges of said flanges of said openings, transparent prisms disposed over said openings and supported upon said flanges thereof and said channel bars, and a filling disposed on said plate and within said channel bars and embedding said prisms the upper faces of said prisms being exposed.
- 45 10. A vault light comprising a plate provided with a plurality of rows of rectangular openings, flanges integral with said plate bordering each of said openings on two opposing sides thereof, channel bars extending over and having the outer faces of their flanges resting upon said plate and secured thereto, said channel bars having the outer faces of their flanges disposed in contact with the side edges of said flanges of said openings, transparent prisms disposed over said openings and supported upon said flanges and said channel bars, said prisms being of greater area on their supported than on their upper faces, flanges on the edges of said plate having their free edges disposed flush with the upper faces of said prisms, and a filling disposed on said plate and embedding said channel bars and said prisms, the upper faces of the latter being exposed.
- 50 In testimony whereof, I have signed my name in presence of two subscribing witnesses.
